UNITED STATES PATENT OFFICE.

EMILE REIZENSTEIN, OF BROOKLINE, MASSACHUSETTS.

PRESSING DEVICE.

Application filed January 19, 1922. Serial No. 530,372.

To all whom it may concern:

Be it known that I, EMILE REIZENSTEIN, a citizen of the United States of America, and resident of Brookline, in the county of Norfolk and State of Massachusetts, have invented new and useful Improvements in Pressing Devices, of which the following is a specification.

This invention relates to pressing devices 10 of the type having pressing members adapted to press articles therebetween and more particularly to devices for pressing trouser legs in which the pressing members are held together with clamps.

15 The objects of the invention are to provide a device of the character referred to which is light and compact and at the same time sufficiently rigid to produce a substantially uniform pressure along a relatively 20 long fold or crease which requires a comparative small number of clamps to hold the pressing members together, which will press both the front and rear creases of one or both legs of a pair of trousers at the same 25 time, which will exert adequate pressure on both creases irrespective of the relatively thick seam portions on the sides of the legs, which can be adjusted to trousers or other articles of different sizes, which can be folded 30 into compact form, which is both adjustable and foldable as aforesaid, and which is generally superior to prior devices of the type referred to.

A pressing device made according to the 35 present invention may have any of the following characteristics. One of the pressing members, which is preferably relatively narrow and located near the edge of the other member, may be adjustable toward and from 40 the edge of the other members to accommodate articles in different positions. For example, in a device having one member somewhat wider than a flattened trouser leg and having a narrow pressing member extending 45 along each edge of said member simultaneously to press both the front and the rear creases of the leg, one or both of the narrow members may be adjusted inwardly and outwardly to accommodate trousers of 50 different sizes or to accommodate different lengths of a tapered trouser leg. To hold the presser members together in various positions of adjustment relatively to each other clamps adapted to engage the members in 55 each of the positions may be provided.

These clips are preferably in the form of U-shaped clips extending over the edges of the presser members. The clips may directly engage the backs of the members but the narrow members are preferably provided 60 with clip bearings (which may be in the form of stiffening ridges hereinafter referred to) and the faces of the clips which engage the bearings are preferably serrated or roughened to hold the parts in position. 65 In order to minimize the number of clamps and at the same time secure approximately uniform pressure throughout the lengths of the presser members stiffeners may be provided, the stiffeners preferably being in the 70 form of ridges extending along the backs of the narrow presser members. These stiffeners are preferably in the form of sheet metal strips having a corrugation or ridge extending longitudinally thereof and having integral tabs extending into or through the narrow presser members to secure the parts together. The stiffeners should be laterally 75 adjustable, especially when serving as bearings for the clamps, so that they may be positioned approximately over the creases of the 80 article to be pressed, thereby to stiffen the presser members along the lines of the creases and to afford maximum pressure along such lines, and when fast to the adjustable presser members the parts are of 85 course adjustable together.

The pressing members may be connected together so that they do not fall apart when unclamped in which case the connection is 90 preferably adjustable to permit the aforesaid adjustment. This may be accomplished by hinging means in the form of a flexible connection of fabric or other suitable material having sufficient slack to permit the adjustment. 95

In order to illustrate the nature of the invention certain concrete embodiments should be shown in the accompanying drawings, in which,—

Fig. 1 is a plan view of a device for pressing trouser legs;

Fig. 2 is a section on line 2—2 of Fig. 1;

Fig. 3 is an end view of one of the presser members;

Fig. 4 is a side view of a modified trouser presser device;

Fig. 5 is a section on line 5—6 of Fig. 4 showing one position of adjustment;

Fig. 6 is a similar view on line 5—6 of 110

Fig. 4 showing another position of adjustment;

Fig. 7 is a perspective view of the preferred form of clamping clip; and

5 Fig. 8 is a side view of a further modification of presser member.

In the device shown in Figs. 1, 2 and 3, one of the presser members 1 is somewhat wider than the trouser legs and is tapered 10 to correspond with the taper of the trousers. The other presser members 2 are in the form of relatively narrow strips extending along the opposite edges of the member 1. Each of the presser members has a stiffener 3 or 3' extending along the back thereof, the stiffener preferably being formed of sheet metal and having a corrugation or ridge 4 or 4' extending longitudinally thereof and having its corners 5 extending 15 through the presser member 2 and bent over as shown at 6 in Fig. 3. By using thin sheet metal the protuberance produced by the turned end 6 is very shallow and if desired the member 2 may be recessed to receive this 20 folded corner so that its outward face is flush with the lower side of the presser member 2.

The clamps 7 for holding the presser members together are U-shaped and adapted 30 to fit over the edges of the presser members as shown in Fig. 2. These clamps may be formed of various materials but they are preferably formed of some metal such as steel which possesses some elasticity. The 35 leg 8 of each clamp is preferably flat while the other leg 9 is preferably shaped as shown in Fig. 7 with an elongate portion 10 substantially parallel to the opposite leg 8. Each face of the clip which engages a metallic ridge is preferably serrated or roughened as indicated at 10 in Fig. 7.

By making the lower member 1, which extends the full width of the device, sufficiently stiff in itself, the lower stiffeners 4' 45 may be omitted, in which case the clamps are formed and applied as shown in Figs. 5 and 6.

In using the device the trousers are laid 50 on the board 1 with their front and rear creases near the opposite edges of the board respectively, the presser members 2 are then placed on the creases and the clamps 7 are then slipped over the edges of the members to press them together. Somewhat better 55 results may be obtained by dampening the folds of the trousers before they are placed in the vise. Either one or both legs of the trousers may be pressed at a time. If the creases of the trousers extend almost to the 60 edges of the board 1 the members 2 may be placed with their outer edges over the edges of the board as shown in Fig. 1 and also in Fig. 2. If the trousers are some narrower 65 the members 2 may be shifted inwardly until the ridges 4 are approximately over the

creases, the clips 7 being adapted to engage the ridges 4 in various positions of adjustment.

The device shown in Fig. 4 is similar to that shown in Fig. 1 except in that the board 70 1' is divided transversely at 9 and the two parts are hinged together by means of a flexible strip of material 10 secured to the bottom of the board on each side of the dividing line 9. The device shown in Fig. 4 75 also differs from that shown in Fig. 1 in that the presser members 2' are divided into parts corresponding to the parts of the board 1' and each part is connected to the corresponding part of the board 1 by means of flexible connections 11, of fibre, leather or the like, connections having sufficient slack between the parts to permit the aforesaid lateral adjustment of the members 2' as 80 illustrated in Figs. 5 and 6.

The device shown in Figs. 4, 5 and 6 may be folded into compact form along the line 9, the presser member 2' remaining attached to the board 1' when folded.

Instead of having the members 2' connected to the board 1' as in Fig. 4, the two parts of each member may be connected together as shown in Fig. 8, where the parts 21 correspond to the parts 2' of Fig. 4 and are hinged together at their meeting ends by a suitable hinge 22. It will be understood that the presser member shown in Fig. 8 is intended to be used with a board which is intended to be folded like the board 1' of Fig. 4.

Many other modifications may be made within the scope of the appended claims but the above specific embodiments will serve to illustrate the genus of the invention.

I claim:

1. A pressing device comprising a plurality of pressing members adapted to press articles therebetween, one of the members being relatively narrow and being located near the edge of the other member, said narrow member being adjustable toward and from said edge to accommodate articles in different positions, and means for clamping the two members together in various positions of adjustment of the narrow member.

2. A pressing device comprising a plurality of pressing members adapted to press articles therebetween, a stiffener extending along the outside of one of said members, and means for pressing said members together, said means engaging said stiffener.

3. A pressing device comprising a plurality of pressing members adapted to press articles therebetween, a clamp extending over the edges of said members for clamping the members together, and a bearing interposed between said clamp and one of said members.

4. A pressing device comprising a plurality of pressing members adapted to press ar-

5 ticles therebetween, a clamp extending over the edges of said members for clamping the members together, and a bearing interposed between said clamp and one of said members, said bearing being mounted on the last mentioned one of said members.

5. A pressing device comprising a pressing board, a pressing member extending along one edge of said board, means connecting said member to said board to permit adjustment of the member toward and from said edge, and means independent of said first named means for clamping said member upon said board.

15 6. A pressing device comprising a plurality of pressing members adapted to press articles therebetween, a stiffening ridge extending along the back of one of said members, and clamps extending over the edges 20 of said members for clamping the members together, said clamps bearing on said ridge.

7. A pressing device comprising a plurality of pressing members adapted to press articles therebetween, a sheet metal stiffening ridge extending along the back of one 25 of said members near the outer edge thereof, said ridge having integral portions extending into said member to anchor the ridge thereto.

30 8. A pressing device comprising a plurality of pressing members adapted to press articles therebetween, a stiffening ridge extending along the back of one of said members near the outer edge thereof, said stiffening ridge being laterally adjustable, and clamps extending over the edges of said 35 members for clamping the members together, said clamps being adapted to bear on said ridge in various adjustments of the 40 ridge.

9. A pressing device comprising a plurality of pressing members adapted to press articles therebetween, one of said members being laterally adjustable relatively to the 45 edge of the other member, a stiffening ridge extending along the back of said adjustable member, and clamps extending over the edges of said members for clamping the members together, said clamps bearing on 50 said ridge in various positions of said adjustable member.

10. A device for pressing trousers comprising a presser board adapted to engage one side of the front and rear creases of a trouser leg near the opposite edges of the 55 board, pressing strips extending along said edges respectively on the other side of said creases, said strips being loosely attached to said board but not to each other to permit relative adjustment transversely of the 60 board, and clamps extending over said edges for clamping said strips and board together.

11. A device for pressing trousers comprising a presser board adapted to engage one side of the front and rear creases of a 65 trouser leg near the opposite edges of the board, pressing strips extending along said edges respectively on the other side of said creases, stiffening ridges extending longitudinally along the backs of said strips, and 70 clamps extending over said edges for clamping said strips and board together, said clamps bearing on said ridges.

12. A pressing device comprising a pressing board, a pressing member extending 75 along one edge of said board, and means connecting said member to said board to permit adjustment of the member toward and from said edge.

13. A pressing device comprising a pressing board, a pressing member extending along one edge of said board, and an adjustable hinging means connecting said member to said board and permitting lateral adjustment of the member relatively to 80 said edge.

14. A pressing device comprising a pressing board, a pressing member extending along one edge of said board, and a flexible connection between said member and 85 said board permitting movement of the member away from the board and also adjustment away from said edge when in use.

15. A pressing device comprising a plurality of presser members adapted to press 90 articles therebetween, stiffeners extending along the outer sides of said members, and means engaging said stiffeners for pressing said members together.

Signed by me at Boston, Massachusetts, 100 this 12th day of January 1922.

EMILE REIZENSTEIN.
